UNITED STATES PATENT OFFICE.

WILLIAM H. DONALD, OF CINCINNATI, OHIO, ASSIGNOR OF ONE-HALF TO FREDERICK A. KNOWLES, AND ONE-FOURTH TO ALANSON A. KNOWLES, BOTH OF CINCINNATI, OHIO.

SLICING MACHINE.

Application filed September 17, 1921. Serial No. 501,248.

To all whom it may concern:

Be it known that I, WILLIAM H. DONALD, a Canadian subject of the King of Great Britain, residing at Cincinnati, in the county of Hamilton and State of Ohio, have invented certain new and useful Improvements in Slicing Machines, of which the following is a specification.

My invention relates to machines for slicing meat and other edibles, in general, and more particularly to the kind disclosed and claimed in my Patent No. 1,362,855, dated December 21, 1920, upon which the present invention is an improvement.

Its object, like that machine, is to make such a machine simple of construction, convenient to use and to keep clean, and reliable and accurate in operation and not readily deranged in its use or by tampering.

An object peculiar to the present invention is to simplify the device that carries the meat toward the cutting member, lightening it and making it more sanitary. Another object is to provide a more compact, substantial and reliable feeding device for the meat-carrier, and to simplify the construction, operation and management of the machine, in general, as compared with my previous invention and other devices for similar purposes. Other objects, peculiar to the present invention, as well as in common with that of the patent mentioned, will appear in the course of the ensuing description.

I attain these objects by the device illustrated, for example, in the accompanying drawings, in which—

Fig. 1 is a general perspective view of a meat-slicer embodying my invention, the view being from the front end and side thereof;

Fig. 2 is an enlarged perspective view of part of the variable feeding mechanism;

Fig. 3 is a similar view of part of the gripper;

Fig. 4 is a top plan view of the machine with the top removed to reveal the interior details, and with parts broken away and omitted for lack of space, and the cutting member being shown in forward position by dotted lines, and in section in its rearward position, to reveal interior details; and

Fig. 5 is a front elevation of the machine, partly in front-to-rear lengthwise section, part of the gripper being omitted for lack of space, and part of a weighing scale being

represented in receiving relation to the machine.

The base 1 is rectangular, supporting the casing 2 of similar shape with a removable top 3 having the cutter-bar 4 along its front edge with a ledge 5 extending down a short distance along the casing front, and having a flange 6 similarly extending down along its rear edge, with a clamp-screw 7 (Fig. 5) engaging the rear end of the casing, by which the top 3 is clamped down on the casing. The upper edges of the lateral sides of the casing 2 are recessed for most of their lengths, leaving the slots 8 under the edges of the top 3. This top 3 is not the full width of the casing, the latter extending therefrom at the far side and containing the cutting-member actuating mechanism, which is similar to that disclosed and claimed in my mentioned patent. This comprises a sleeve 9 journaled in a bracket 10 and in the front end of the casing 2, projecting forward from said end and having fixed on it the hollow arm 11 extending up and having the cutter shaft 12 journaled in its upper end part, preferably in ball-bearings 13, with a bevel gear 14 fixed on this shaft between the bearings and facing forwardly. A shaft 15 is journaled in the sleeve 9, with a bevel gear 16 at the front end; and a shaft 17 is journaled lengthwise in the hollow arm 11, with the bevel gears 18 and 19 meshing, respectively, with this front bevel gear 16 and the cutter-shaft bevel gear 14.

The main driving shaft 20 is journaled transversely of the casing, preferably in ball bearings 21 on the casing sides; and a bevel gear 22, fixed on this shaft 20, meshes with a bevel pinion 23 fixed on the shaft 15 at the rear end of the sleeve 9. A spur gear 24 is mounted on this driving shaft 20, and a larger spur gear 25 is journaled in the front part of the casing 2, in mesh with the gear 24. Preferably these gears 24 and 25 have spiral teeth, for strength and quietness of running. The collar 26, fixed on the sleeve 9 by a set screw 27, between the sleeve bearings, is straddled by a yoke arm 28 having trunnion connections with the collar 26 and projecting toward the large gear 25, with a pin 29 slideable in the yoke arm 28 and pivoted to the side of the gear 25; so that rotation of the gear 25 oscillates the collar 26, sleeve 9 and hollow arm 11. This mechanism being clearly shown in my patent men-

tioned, where it is claimed, I dispense with extensive illustration thereof herein.

The bevel-gear driving connection in the arm 11, however, is novel herein; being an improvement over the chain connection in my prior patent. Also, the smaller spur gear 24 is mounted on the driving shaft 20 in a novel manner. A flange 30 is fixed to the shaft 20 at the far side of the gear 24, and 10 a similar flange 31 slides on the shaft 20 at the near side. This shaft 20 extends out through the near side of the casing 2, where it has the hand-wheel 32 fixed on it, and from the flange 31 out to this end, this shaft 15 20 is hollow, with slots 33 at the inner end of this hollow part, carrying a key 34 projecting out and engaging in notches in the hub of the flange 31. A clamping-stem 35 occupies the hollow interior of the shaft 20, 20 with its inner end abutting the key 34, and with threads 36 in the enlarged and tapped near end of this interior, and a knurled head 37 at the near end of the shaft for screwing the stem inward or outward.

25 The cutter 38 is a dished disk, removably keyed on the rear end of the cutter-shaft 12, and guarded by the similarly shaped guard 39, fixed on the arm 11 in front of the cutter and cut away at the front to expose the disk edge of the cutter 38, which is so positioned as to pass closely along the edge of the cutter-bar 4, coacting therewith to cut the meat or other substance projected over this bar 4, as the arm 11 swings forwardly. In the rear part of the guard 39 a grinding attachment 40 is mounted (Fig. 1) which not being in itself of my invention, but being known in the art, needs no detailed illustration, and may be described as abrasive means suitably mounted to properly grind the cutting disk edge when the disk is rotated.

The feeding device comprises the carriage frame 41 of rectangular open formation, lying under the top 3 of the casing 2, and guided forwardly and rearwardly by the guide-bar 42 having its ends fixed to the upper parts of the casing front and rear ends; lugs 43 fixed on the frame 41 flanking the bar 42 at front and rear. At its front end, this frame 41 has ears 44 and 45, respectively, at the far and the near side, projecting laterally past the respective edges of the top 3. The post 46 is fixed in and extends up from the far ear 44, and is smooth; and the post 47 is similarly mounted in the near ear 45, with notches 48 on its inner side. The ears 44 and 45 project up very slightly above the plane of the upper surface of the top 3, and the lower gripper-bar 49 lies across on these ears, with end recesses 50 receiving the posts 46 and 47 loosely. The upper surface of this bar 49 has front-to-rear corrugations 51 from near one end to near the other end; and preferably it is slightly

wedge-shaped in cross-section and placed so that its corrugated top inclines downward forwardly (Fig. 5). The upper gripper-bar 52 has end hubs 53 and 54 embracing the posts 46 and 47, respectively, and is hollow. In the top of its interior, the detent-bar 55 is slidably mounted, pressed by a spring 56 to engage in the notches 48 of the post 47, and withdrawn from these notches by a handle-lever 57 pivoted in a slot in the top of the bar 52 and projecting up under a bail-like handle 58 forming part of the bar 52; the lower inner end of this lever engaging in a notch in the detent bar 55 (Fig. 3.) This upper gripper-bar 52 has downwardly projected teeth 59 at intervals across the machine, to enter the meat or other substance resting on the lower gripper-bar 49, between the posts 46 and 47; thus broadly resembling such bar in my prior patent mentioned.

In my present invention, however, I make these teeth 59 removable for sharpening or renewal, in a convenient manner. The lower part of the front wall of the hollow upper gripper-bar 52 has openings 60, and a fastening-bar 61 (Fig. 3) lies along on the bottom of the interior of the bar 52, against its front wall, with meeting lower and rear recesses 62. Each tooth 59, tapering downward in its straight lower part, curves back and then abruptly upward in its upper part; being slipped backward and upward through the bar opening 60, and the fastening-bar 61 being secured down on the gripper-bar bottom by the screws 63, with the teeth 59 gripped in their curves by the walls of the recesses 62 and of the openings 60, so that the teeth are rigidly held to project down at the front of the upper gripper-bar 52. If the fastening-bar 61 is loosened, it permits the teeth to be pulled forward and downward out of the recesses 62 and openings 60; the curves being such that this can be done by variously tilting the teeth. This allows renewal of bent or dulled teeth.

The top surface of the removable casing top 3 preferably is made of glazed tile or other material used for sanitary surfaces; and, as shown in Fig. 1, a shelf 64 projects forward from the bottom of the front end of the casing 2, under the cutter-bar 4, to receive the slices cut from the meat or other object projected over the front end. In Fig. 5, this shelf 64 is omitted to admit the receiving end of the weighing scale 65, upon which the slices are delivered as cut, ready for weighing; and the scale is thus adapted directly to indicate when the operation of the machine is to be stopped, in supplying a required amount of the sliced meat or other substance. This is an advantage of having the cutting member to move across the front of the cut substance instead of having the substance moved to the cutter

in the cutting stroke; as the place of delivery of the slices is coextensive with the cut, and not at one end thereof. By having the shelf 64, or slab 65 of the scale, or other 5 slice-receiving element, spaced down from the cutting device operating in the manner disclosed, the slices fall flat on the receiving element, one above the other, ready for wrapping with a minimum of rearranging; 10 and not curled and tangled as with slices delivered at the end of a cut.

The rack-bar 66 is fixed on the frame 41, with its teeth laterally inward. The yoke 67 comprises an upper and a lower member extending forwardly from a hub connected to the front end of a shifter-bar 68 which extends back through a slot 69 in the rear end of the casing 2, to lie at one side or the other of a lug 70 projecting up from the 20 lower edge of the slot 69. The front end parts of the yoke members have hubs embracing an upright shaft 71 in a bracket 72 fixed to the adjacent side of the casing 2, so that this yoke can swing transversely with 25 the shifter-bar 68; and the shaft 71 also can turn in the bracket 72. A pinion-shaft 73 is journaled upright in the yoke members about midway of their length; and between these members it has the large ratchet-wheel 30 74 fixed on it, above, and has the small pinion 75 rotatable on it, below. A lever 76 is fixed to the pinion 75 and projects back at the far side, with a pawl 77 on it spring-pressed against the teeth of the ratchet-wheel 74. Above the upper yoke member, the pinion 78 is fixed on the shaft 73, to mesh with the carriage rack-bar 66 or unmesh therefrom, accordingly as the yoke 67 is held by the shifter-bar 68 being at the 35 near or the far side of the lug 70. A segment-gear 79 is fixed on the shaft 71 at the front end of the yoke 67 next to the lower member thereof, and meshes with the small pinion 75 that carries the pawl arm 76. 40 Above the upper yoke member, the driving-arm 80 is fixed on this shaft 71, projecting forwardly and over toward the large spur gear 25, which has a segmental cam-rib 81 on its adjacent side, sloping in both directions circumferentially from near its middle (Fig. 4,) on which cam-rib 81 the driving-arm 80 has a roller 82. A spur 83 projects from the hub of the driving-arm 80, forwardly at the near side, with a spring 84 stretched from its end part forwardly to the front end of the casing 2; thus holding these parts so that the roller 82 always bears toward the gear 25 to ride in and out on the cam-rib 81 as the latter passes the roller. A 50 detent pawl 85 is pivoted on the near side of the hub part of the yoke 67 and is spring-pressed against the teeth of the ratchet-wheel 74.

Above the segment-gear 79, under the upper yoke member, a hub is fixed on the shaft

71, with a controlling-spur 86 projected forwardly. The controlling shaft 87 is journaled in the upper part of the adjacent side of the casing 2, near the front end thereof, in a suitable bearing hub attached to the casing side, and outside the casing a dial-plate 88 is fixed to the casing side around this shaft 87, and a knob having a coacting dial-plate 89 is fixed on the shaft to bear in against the fixed dial-plate 88. On the inner end of this shaft 87 is fixed the controlling cam 90, which is cylindrical with a flange around it having a lateral face receiving the end of the controlling spur 86 under the tension of the spring 84 attached to the spur 83 on the arm 80 on the same shaft with this controlling-spur 86. This lateral face of the cam flange follows a helix around the cam. A spring 91 around the shaft 87 is compressed between the adjacent ends of the cam 90 and the bearing hub in which the shaft is journaled, holding the shaft 87 and connected parts inward with the dial plates 88 and 89 in firm frictional contact. Graduations on the dial-plates serve to indicate various adjustments made by turning the shaft 87 and cam 90, presenting more or less prominent parts of the helical face of the cam flange to the spur 86.

Operation.—The body of substance, as meat, to be sliced is placed on the lower gripper-bar 49 between the posts 46 and 47 while the upper gripper-bar 52 is raised by grasping the handle-lever 57 along with the bar handle 58, releasing the detent-bar 55 from the post notches 48. Then this upper bar 52 is pressed down, its teeth 59 enters the substance, and the detent-bar 55 engages in one of the post notches 48, holding the substance firmly against lateral movement by the engagement of these teeth 59 above and of the corrugations 51 of the lower bar 49 below. This will be done with the feeding device set back along the casing top 3 to the limit of its rearward travel, or any distance less than that, depending somewhat upon the firmness of the substance. Thus a firm substance can have a greater initial forward projection from the gripping device and properly support itself at the front end against the pressure of the cutter, than can a less firm substance. This initial adjustment of the feeding device can be effected manually, swinging the yoke 67 to unmash the pinion 78 from the rack-bar 66 and moving the feeding device backward by grasping the handle 58 thereof. The rear part of the substance, as the piece of meat, rests on the top 3 to the rear of the gripping device; and as the gripping and feeding device travels forward, drags on this top. This dispenses with the table of my prior patent for carrying the substance, minimizing the weight of the traveling parts and the surfaces to be kept clean.

- The controlling-cam 90 is set, with the aid of the dial graduations, to determine the thickness of the slices to be cut, as the substance is fed forward step by step each time
- 5 the arm 11 is swung back away from the substance. The yoke 67 being shifted until the shifter-bar 68 is at the near side of the lug 70, at the rear end of the machine, and the stem 35 being screwed in tightly by its
- 10 knob or head 37 at the center of the hand-wheel 32, the pinion 78 is meshed with the rack-bar 66 to feed the substance forward, and the small spur gear 24 is clamped tightly between the two flanges 30 and 31 on the
- 15 driving shaft 20, to drive the large spur gear 25 and thus oscillate the cutter arm 11 by means of the yoke arm 28, and oscillate the feeding mechanism parts by means of the cam-rib 81.
- 20 The hand-wheel 32 is turned over backwardly, rotating the large spur gear 25 forwardly; and as the pivotal connection of the yoke-arm 28 reaches the highest position the arm 11 and cutting disk 38, which is being rotated rapidly over and downwardly past the cutter-bar 4, reaches its farthest withdrawn position, the cam-rib 81 has been carried by the gear 25 against the roller of the driving-arm 80, acting, against the tension of the spring 84 and through the medium of the shaft 71, segment-gear 79, pinion 75, lever 76 and pawl 77 to turn the ratchet-wheel 74, which turns the pinion 78, acting on the rack-bar 66 to advance the carriage-frame 41 forwardly. Then as the gear 25 continues to rotate, carrying the cam-rib 81 past the roller 82, the spring 84 pulls the parts back for the pawl 77 to engage with less advanced ratchet-wheel
- 25 teeth; while the yoke-arm 28, carried forward and downward, swings the arm 11 and rapidly rotated cutting-disk 38 along the cutter-bar 4, through the meat or other substance just fed forward thereover, slicing off the projected part, to fall flatwise on the shelf 64 (Fig. 1) or on the receiving slab of the weighing-scale 65 (Fig. 5).
- 30 If the controlling-cam 90 was set so that a more prominent part of its helical flange
- 35 face was opposite the controlling spur 86, this spur engaging this face will prevent, through the medium of the shaft 71, the return of the driving-arm 80 toward the gear 25 in proportion to the prominence of this part of the cam 90, and consequently the pawl 77 will, through the operative connections with the arm 80, be prevented from traveling back over teeth of the ratchet-wheel 74 in like proportion. Thus, the less
- 40 prominent part of the cam 90 presented toward the spur 86, the greater will be the ratchet return and the greater will be the ratchet feed when the cam-rib 81 passes against the roller 82, using more or less of the projection of this cam-rib 81 as driving

means accordingly as less or more prominence of the controlling cam 90 is permitted by its adjustment, guided by the dial-plates 88 and 89, with greater or less thickness of the slice thus cut off. The dial-plate graduations having a known relation to the thickness, the machine thus can be adjusted to cut slices of any required thickness, and the firm frictional holding of the controlling means by these dial plates permits indefinite adjustments which some positive holding means, as in my prior patent, does not, yet holds the controlling means in its adjusted position, against accidental displacement or tampering, as by children in stores, better than the device of that patent.

The clamping-stem 35 may be used to render the machine inconvenient for unauthorized use, by loosening it, upon which turning the hand-wheel 32 only will rotate the cutting disk 38, but will not swing it, and will not operate the feeding device, because the small spur gear 24 will be unclamped from the driving shaft 20 and will not turn the large spur gear 25 as is necessary to operate the arm 11 and the feeding mechanism. In my prior patent, the releasing means is inside the casing of the machine and is a positive clutch held by a set-screw, requiring removal of the casing top to disconnect it. By my present invention, the user can render the machine inoperative after each use, simply by turning a knob at the handwheel. When the cutting disk 38 is to be ground, as by the grinding means 40, this release by means of the clamping-stem 35 permits rotation of the disk 38 without oscillation thereof and without operating the feeding device.

Guiding the feeding carrier by the bar 42 and limiting the extent of the carrier above the casing top 3 to a minor extent of this top avoids extensions along the sides of the top except the ears 44 and 45 and their posts 46 and 47; thus making it very easy to keep the top clean, as well as affording a better guidance than with engaging means along the top edge, as in my prior patent. The rack-and-pinion feed is adapted to be formed more accurately than is the highly pitched screw feed of the prior device; and the more accurately guiding bar facilities the use of this improved feed. Also, nearly all of the feed mechanism is carried on the yoke 67, and not dispersed throughout the casing as in the prior invention. The mechanism thus is more reliable on account of being mounted on a single mounting; and is more readily accessible, as it can be removed as a unit, on this yoke, leaving the other mechanisms fully accessible, after the casing top 3 and carriage frame 41 are removed.

The disclosed construction is preferred, but variations will occur under different conditions and in different types of machines.

Therefore, while certain constructional details are deemed preferable in connection with my invention, and I have shown and described these rather specifically in elucidating the construction and use of my invention, as is required, I do not wish to be understood as being limited to such precise showing and description, but having thus fully described my invention, what I claim 10 as new and desire to secure by Letters Patent is:

1. In combination with a stationary support, a cutter, and cutting mechanism, a carrier, a guide-bar fixed on said support, means on said carrier guidingly engaging with said guide-bar, a rack fixed on said carrier, a yoke on said support, a pinion mounted on said yoke and meshing with said rack, feeding mechanism operatively related to said cutting mechanism and said pinion, and means on said carrier extending across a minor part of said support, to engage an object and drag said object along said support toward said cutter, whereby 25 said object meets said cutter.

2. In combination with a stationary support, a cutter, and cutting mechanism, a carrier, a guide-bar fixed on said support, means on said carrier guidingly engaging with said guide-bar, a rack fixed on said carrier, a yoke on said support, a pinion mounted on said yoke and meshing with said rack, and feeding mechanism operatively related to said cutting mechanism and said 35 pinion.

3. In combination with a stationary support, a cutter, a cutting mechanism, a carrier, a rack fixed on said carrier, a yoke on said support, a pinion mounted on said 40 yoke and meshing with said rack, and feeding mechanism operatively related to said cutting mechanism and said pinion.

4. In combination with a stationary support, a cutter, and cutting mechanism, a carrier, a rack fixed on said carrier, a yoke pivoted on said support, a pinion mounted on said yoke and meshing with said rack or unmeshing from said rack upon swinging of said yoke, and feeding mechanism operatively related to said cutting mechanism and said pinion.

5. In combination with a stationary support, a cutter, and cutting mechanism, a carrier, a rack fixed on said carrier, a pinion supported on said support and meshing with said rack, feeding mechanism operatively related to said cutting mechanism and said pinion, and means for varying the operative relation of said feeding mechanism to said cutting mechanism.

6. In combination with a stationary support, a rotatable cutter mechanism for rotating said cutter, a carrier, mechanism for causing relative cutting movement of said cutter and said carrier, feeding mechanism

for feeding said carrier toward said cutter, driving means operatively related to said cutter-rotating mechanism, and means accessible outside said support for operatively relating said driving means to said feeding mechanism and to said mechanism for causing said relative cutting movement.

7. In combination with a stationary support, a rotatable cutter mechanism for rotating said cutter, a carrier, mechanism for causing relative cutting movement of said cutter and said carrier, feeding mechanism for feeding said carrier toward said cutter, a handwheel operatively related to said cutter-rotating mechanism, and means accessible at said handwheel for operatively relating said handwheel to said feeding mechanism and to said mechanism for causing said relative cutting movement.

8. In combination with a stationary support, a cutter, and cutting mechanism, a carrier, feeding mechanism operatively related to said cutting mechanism and said carrier, and a controlling-cam rotatably mounted on said support and engaging a part of said feeding mechanism to vary the feeding of said carrier.

9. In combination with a stationary support, a cutter, and cutting mechanism, a carrier, feeding mechanism operatively related to said cutting mechanism and said carrier, a controlling-cam rotatably mounted on said support and engaging a part of said feeding mechanism to vary the feeding of said carrier, an element fixed to said support, an element connected to said controlling-cam, and means holding said elements in frictional contact to hold said controlling-cam in various feed-controlling adjustments.

10. In combination with a stationary support, a cutter, and cutting mechanism, a carrier, a rack fixed on said carrier, a yoke on said support, a pinion mounted on said yoke and meshing with said rack, a ratchet-wheel coaxially fixed to said pinion, a pawl engaging with said ratchet-wheel, and feeding mechanism operatively related to said cutting mechanism and said pawl.

11. In combination with a stationary support, a cutter, and cutting mechanism, a carrier, a rack fixed on said carrier, a yoke on said support, a pinion mounted on said yoke and meshing with said rack, a ratchet-wheel coaxially fixed to said pinion, a lever and a gear fixed together and pivoted on said yoke, a pawl on said lever engaging with said ratchet-wheel, a segment-gear pivoted on said yoke and meshing with said gear, an arm fixed to said segment-gear, a cam rotated by said cutting mechanism, and a spring holding said arm toward said cam.

12. In combination with a stationary support, a cutter, and cutting mechanism, a carrier, a rack fixed on said carrier, a yoke on said support, a pinion mounted on said

yoke and meshing with said rack, a ratchet-wheel coaxially fixed to said pinion, a lever and a gear fixed together and pivoted on said yoke, a pawl on said lever engaging with 5 said ratchet wheel, a segment-gear pivoted on said yoke and meshing with said gear, an arm fixed to said segment-gear, a cam rotated by said cutting mechanism, a spring holding said arm toward said cam, a controlling- 10 spur fixed to said arm, a controlling-cam journaled on said support for rotation to variably engage said spur, and frictionally contacting elements on said support and turning with said cam, respectively, to hold 15 said cam in various stages of rotation.

13. In combination with a stationary support, a rotatable cutter, mechanism for rotating said cutter, a carrier, mechanism for causing relative cutting movement of said cutter 20 and said carrier, feeding mechanism for feeding said carrier toward said cutter, a driving shaft having an end outside said support, and having a hollow interior opening through said end and a slot opening from 25 said interior inside said support, a gear loose on said shaft, clamping means on said shaft to clamp said gear to said shaft, said gear being operatively related to said cutting and feeding mechanisms to drive said mechanisms 30 when thus clamped, a clamping-stem screwed into said hollow interior and accessible for turning at said shaft end, means ex-

tending out through said slot, engaged by 35 said stem, to clamp said clamping means, and an operative connection from said driving shaft to said cutter, to rotate said cutter independently of the clamping of said gear.

14. In combination with a stationary support, a carrier on said support, an arm swinging on said support across said carrier, a rotatable cutter on said arm, a bevel gear coaxially fixed to said cutter, a shaft coaxial to the swinging of said arm but rotatable independently thereof, a shaft journaled along 40 said arm, bevel gears fixed on the respective 45 shafts and meshing together, a bevel gear fixed on said shaft journaled along said arm, meshing with said bevel gear fixed to said cutter, mechanism for rotating said shaft coaxial to said swinging of said arm, and 50 mechanism for feeding said carrier toward said swinging arm and cutter.

15. In a device of the character described, a stationary support, a cutter, a carrier, a removable top for said support having engaging means extending down along opposite 55 ends of said support, a clamping screw in one of said engaging means, bearing against the adjacent end of said support, and mechanism for operating said cutter and said 60 carrier, in said support and under said removable top.

WILLIAM H. DONALD.
